UNITED STATES PATENT OFFICE.

KARL D. WILLMS, OF BALTIMORE, MARYLAND.

SNOW GUARD.

Application filed December 2, 1926. Serial No. 152,223.

The invention relates to improvements in snow guards for roofs and has reference more particularly to one designed primarily for use with shingle roofs.

5 It is the object of the invention to provide a snow guard of new and improved construction, formed from a single length of wire and bent in such a manner as to produce a very rigid and effective structure 10 which may be quickly and easily attached.

With the foregoing in view, the invention resides in the novel subject matter herein-after described and claimed, the description being supplemented by the accompanying 15 drawing.

Fig. 1 is a vertical section through a portion of a roof showing the invention applied thereto.

Fig. 2 is an elevation of the parts shown 20 in Fig. 1 looking in the direction of the arrow A.

Fig. 3 is an enlarged side elevation of the guard.

Fig. 4 is a top plan view.

25 Fig. 5 is a transverse sectional view on line 5—5 of Fig. 3.

In constructing the device, I make use of a single length of stiff wire having a straight end portion 6 constituting a shank to lie between the edges of two adjacent shingles and to be, when applied, interposed between an overlying shingle and an underlying shingle. The wire at the upper end of this shank is bent downwardly and sharpened to provide 30 an attaching shank 7 to be driven into the sheathing of the roof, and at the lower end of the shank, the wire is bent first upwardly and then downwardly to provide an arched portion 8. From this portion 8, the wire 35 extends in a down-roof direction, on a straight line, forming a base portion 9 to contact with the underlying shingle. At the lower end of this base portion, the wire is bent upwardly at an acute angle to provide 40 a brace 10, and at the upper end of this brace, the wire is curved laterally in one direction and downwardly to provide one- 45

half of an annular snow stop 12, said half being denoted at 11. After forming this half, the wire is coiled tightly around the 50 arched portion 8 as indicated at 13 and from this coil, said wire is curved laterally and upwardly to provide the other half 14 of the stop 12, and the free end 15 of the wire, after forming said stop-half 14, lies against 55 the up-roof side of the half 11.

By employing the novel construction herein shown and described, the guard may be easily and inexpensively manufactured, may be sold at small cost, may be quickly and 60 easily applied at intervals during the laying of a shingle roof, and when so applied, will be efficient to hold snow against sliding from the roof. The construction of the snow stop 12, with its lower portion 13 65 coiled about the arch 8, gives an exceptionally strong construction and moreover this stop is effectively supported by the brace 10 and the base portion 9 with which the lower end of said brace is connected. 70

I claim:—

A snow guard comprising a single length of wire having a straight end portion constituting a shank for anchorage upon a roof, the wire at the lower end of said shank being arched and then extended on a straight line in a down-roof direction from the arch, forming a base portion to rest on the roof, the wire being bent upwardly at an acute angle at the lower end of said base portion so to provide a brace, said wire being curved laterally in one direction and downwardly from the upper end of the brace to the aforesaid arched portion and being coiled tightly around this portion to form one half of an 85 annular snow stop, the wire being then curved laterally in the other direction and upwardly from the coil to form the other half of said annular stop, the free end of said wire lying against the up-roof side of 90 the first named stop half.

In testimony whereof I have hereunto affixed my signature.

KARL D. WILLMS.
